UNITED STATES PATENT OFFICE.

MASSEY P. JENKINS, OF NEWPORT NEWS, VIRGINIA.

SEALED LOCK FOR CAR-DOORS.

1,349,280.

Specification of Letters Patent. Patented Aug. 10, 1920.

Application filed September 6, 1919. Serial No. 322,010.

To all whom it may concern:

Be it known that I, MASSEY P. JENKINS, a citizen of the United States, residing at Newport News, in the county of Warwick 5 and State of Virginia, have invented new and useful Improvements in Sealed Locks for Car-Doors, of which the following is a specification.

The object of my present sole invention 10 is the provision of a car door lock susceptible of being sealed through the medium of an extremely simple and easily applied sealing element, and one that is adapted to be expeditiously and easily manipulated, 15 and in which the elements are so relatively arranged that the car door cannot be released without the seal being destroyed to such an extent as to make the surreptitious opening of the door readily apparent.

20 To the attainment of the foregoing, the invention consists in the improvement as hereinafter described and definitely claimed.

In the accompanying drawings, hereby made a part hereof:

25 Figure 1 is a side elevation showing a car door locked in accordance with my invention.

Fig. 2 is a vertical section taken in a plane parallel to Fig. 1.

30 Fig. 3 is a view taken at right angles to Fig. 2 and showing the lock in elevation.

Fig. 4 is a horizontal transverse section taken in a plane indicated by the line 4—4 of Fig. 2.

35 Fig. 5 is a plan view showing the head on the locking bolt.

Similar numerals of reference designate corresponding parts in all of the views of the drawings.

40 The car body is indicated by 1 in Fig. 1, and the door, indicated by 2, is of the sliding type. On the door is a hasp 3 slotted as shown to receive the staple 4 of my lock, in which staple is a vertically disposed aperture 5,

45 Fig. 2. The said staple 5 is carried by and projects laterally from the base plate 6 of the lock casing; the said base plate 6 being designed to be fixed at the point 7 to the opposite wall of the car body.

50 In addition to the base plate 6, the lock casing, represented at 8, is provided on its wall toward the end of the door 2, with parallel and apertured ears 9, and in said wall the casing is provided with an aperture 10. Above the ears 9 the base wall al-

luded to is provided with a lug 11 in which is a socket 12.

In the upper end wall of the casing 8 is an opening 13, surrounded by an upstanding flange 13^a.

Movable vertically in the casing 8 is a locking bolt 14, having in one side a vertically extending slot 15, and also having a reduced lower portion 16 which extends through an aperture in the lower end wall 65 of the casing and is designed to rest in the staple 4 and at the outer side of the hasp 3 so as to retain the latter on the staple. Formed integral with or permanently fixed to the upper end of the locking bolt 14 is a 70 head 17 in the under side of which is a groove 18 to receive the before-mentioned flange 13^a, this with a view to excluding rain from the interior of the lock, and also with a view to breaking joints so as to 75 render it practically impossible for an instrument to be inserted in an attempt to raise the bolt 14. At one end the head 17 is provided with a lateral extension 19 in which is an aperture 20.

80 Disposed in the casing in parallel relation to the bolt 14 is a movable guard member 21 having a tongue 22 disposed in the slot 15 of the bolt 14 and also having a tubular upper portion. Seated in said 85 tubular upper portion of the member 21 and interposed between the bottom wall thereof and a retaining pin 23 depending from the top wall of the casing, is a coiled spring 24 which is employed to yieldingly 90 hold the member 21 in its lowermost position and to move said member 21 downwardly, as hereinafter described.

95 Looped through the aperture 20 in the bolt head is a seal strip 25 which is formed of a single piece of sheet-metal with apertures adjacent to its ends, and is therefore susceptible of production at extremely small cost.

100 Fulcrumed between the ears 9 is a lever 26, on the upper arm of which is a stud 27 to enter the apertures in the sealing strip 25 and to seat in the socket of the lug 11. On its lower arm the lever 26 is provided with an inwardly extending projection 28 105 which is designed to coöperate with the lower end of the guard member 21, as hereinafter described.

110 My novel lock is shown in Fig. 2 as locking the door, and when it is desired to un-

lock the door, the sealing strip 25 is severed or broken, whereupon the bolt 14 may be freely moved upwardly in order to release the door hasp 3. The bolt 14 cannot, however, be entirely withdrawn from the casing, inasmuch as the bottom wall of the kerf 15 will bring up against the tongue 22 on the guard member 21. When the bolt 14 is moved upwardly as stated, the bottom wall 10 of the slot 15, bringing up against the tongue 22 will raise the guard member 21 until the lower end thereof is clear of the projection 28 on lever 26, whereupon the lower arm of said lever may be swung inwardly and the 15 upper arm thereof swung outwardly. In the latter position of the lever, the broken or severed sealing strip may be readily removed from the stud 27 of the lever.

In locking a door through the medium of 20 my improvement, the hasp is positioned over the staple and a fresh sealing strip is looped through the aperture 20 in the joint head and is engaged with the stud 27 as shown, whereupon the upper arm of the lever 26 is 25 moved inwardly to seat the stud 27 in its socket. It will be understood in this connection that the bolt 14 is moved downwardly precedent to the engagement of the sealing strip 25 with the lever stud 26, and 30 that following such engagement and the attendant inward movement of the upper arm of lever 26 and the outward movement of the lower arm of said lever, the spring 24 will force the guard 21 downwardly to the 35 position shown in Fig. 2, whereupon the guard member 21 will prevent inward movement of the lower arm of the lever 26 and will preclude opening of the lock without severing or breaking of the sealing strip 25.

Having described my invention, what I 40 claim and desire to secure by Letters-Patent, is:

1. A sealed lock comprising a casing, a rectilinearly movable bolt having a longitudinal slot in its side and also having a head on which is an apertured extension, a 45 movable guard member disposed in the casing alongside the bolt and having a tongue arranged in the slot of the bolt, a spring interposed between said guard member and an opposed abutment in the casing, a sealing strip looped through the aperture in the bolt head and having apertures adjacent to its ends, and a lever fulcrumed at an intermediate point of its length on the casing and having on one arm a stud to enter the apertures in the sealing strip and also having on its other arm a projection movable inwardly through an aperture in a wall of the 50 casing when the guard member is clear of 55 said aperture.

2. A sealed lock comprising a casing, a rectilinearly movable bolt having a longitudinal slot in its side and also having a head on which is an apertured extension, a 65 movable guard member disposed in the casing alongside the bolt and having a tongue arranged in the slot of the bolt, a spring interposed between said guard member and an opposed abutment in the casing, a sealing 70 strip looped through the aperture in the bolt head and having apertures adjacent to its ends, and a lever fulcrumed at an intermediate point of its length on the casing and having on one arm a stud to enter the apertures in the sealing strip and also having on its other arm a projection movable inwardly 75 through an aperture in a wall of the casing when the guard member is clear of said aperture; the joint between the casing and the bolt head being broken, and the spring being socketed in the guard member, and the casing being provided with a socket to receive the lever stud.

3. A sealed lock comprising a casing, a 80 movable bolt therein, a guard member also movable in the casing, a spring to move the guard member in one direction, said guard member being movable by the bolt in the opposite direction, a lever, a sealing strip 85 to connect the bolt and the lever, and means on the lever and coöperating with the guard member to prevent disconnection of the sealing strip from the lever when the guard member is one position and to permit such 90 disconnection when the guard member is in another position.

4. A lock comprising a casing, a bolt, a guard member movable in the casing and engaged with the bolt, a spring to move the 100 guard member in one direction, a lever, and a seal to connect the bolt and the lever; said lever having means to coöperate with the guard member whereby in one position of the guard member disconnection of the seal 105 from the lever will be prevented and in another position of the guard member such disconnection will be permitted.

5. The combination in a lock, of a casing, 110 a bolt, a movable guard member, and a movable member adapted for connection through sealing means with the bolt; said movable member having means to coöperate with the guard member whereby in one position of the guard member disconnection of the sealing 115 means from the movable member will be prevented and in another position of the guard member sealing means may be connected with the movable member.

In testimony whereof I affix my signature. 120

MASSEY P. JENKINS.
